UNITED STATES PATENT OFFICE.

GEORGE WILLIAM CLEWELL, OF READING, PENNSYLVANIA.

DESIGN FOR A SAD-IRON HOLDER.

SPECIFICATION forming part of Design No. 30,013, dated January 17, 1899.

Application filed December 20, 1898. Serial No. 699,868. Term of patent 14 years.

To all whom it may concern:

Be it known that I, GEORGE WILLIAM CLEWELL, of Reading, in the county of Berks and State of Pennsylvania, have invented and produced a new and original Design for a Sad-Iron Holder, of which the following is a full, clear, and exact specification.

Reference is to be had to the accompanying drawings, forming a part of this specification, in which similar characters of reference indicate corresponding parts in both the views.

Figure 1 is a perspective view of a sad-iron holder, showing my design; and Fig. 2 is a side elevation of the same.

The design in its entirety consists of a plate A, ornamented at its sides and back with an upwardly-extending flange B, terminating at

its ends in eyes C, projecting forward of the front edge of the plate, above the free end of the plate and somewhat at the side thereof, ²⁰ the vertical flange B at its middle portion and on the outside being ornamented by a horizontal flange, and from the under side of the plate A depend a plurality of lugs E.

The leading feature of the design consists ²⁵ of the plate flanged as described.

I claim—

The design for a sad-iron holder, as herein shown and described.

GEORGE WILLIAM CLEWELL.
